Attorney

UNITED STATES PATENT OFFICE.

BYRD W. BALLOU, OF BUFFVILLE, KANSAS.

DESIGN FOR A BRICK.

47,844.

Specification for Design.

Patented Sept. 21, 1915.

Application filed May 26, 1915. Serial No. 30,691. Term of patent 14 years.

To all whom it may concern:

Be it known that I, BYRD W. BALLOU, a citizen of the United States, residing at Buffville, in the county of Wilson and State of Kansas, have invented a new, original, and ornamental Design for Brick, of which the following is a specification, reference being had to the accompanying drawing, forming part thereof.

In the drawing the figure is a perspective view of the brick of this invention.

I claim:

The ornamental design for a brick, as shown.

BYRD W. BALLOU.

Witness:

MARIE LEMON.
